E. N. DODGE, OF PLAINVIEW, MINNESOTA.

Letters Patent No. 64,290, dated April 30, 1867.

IMPROVEMENT IN WHIFFLE-TREES.

The Schedule referred to in these Letters Patent and making part of the same.

TO ALL WHOM IT MAY CONCERN:

Be it known that I, E. N. DODGE, of Plainview, in the county of Wabasha, and State of Minnesota, have invented certain new and useful Improvements in Whiffle-Trees; and I do hereby declare that the following is a full, clear, and exact description of the same, reference being had to the accompanying drawings, and to the letters of reference marked thereon.

In the annexed drawings, making part of this specification; A represents the cross-bar, which unites the two shafts of a vehicle, and to which the whiffle-tree is usually attached. Pivoted near the ends of this cross-bar are two draught-rods B B, which are provided on their outer ends with the usual catches for holding the tugs. The rear ends of these rods B B are made nearly disk-shaped, and are provided with teeth, as shown, which gear into the teeth of a sliding bar C. The bars C C are provided with arms E E, and these arms are connected together by means of a rod, D. This rod may be secured permanently to one of the arms, and pass through an opening in the other, and have a nut passed over a thread upon its end to regulate the set of the rods B B. a represents the nut upon the end of the rod D. By shortening the rod D in screwing up the nut a, the arms B B are thrown back at their outer ends, and the traces are thus made shorter, or by lengthening the rod the traces are lengthened. It will readily be seen that when the traces are fastened to the ends of the rods B B, they have the see-saw motion incident to traces from the motion of the horse's shoulders. With this arrangement of devices the ordinary whiffle-tree may be dispensed with, and the cross-bar connecting the shafts be made to answer instead.

Having thus fully described my invention, what I claim as new, and desire to secure by Letters Patent, is—
The arrangement of the rods B B, the bars C C, and the connecting-rod D, constructed and used as and for the purpose herein specified.

As evidence that I claim the foregoing I have hereunto set my hand in the presence of two witnesses.

E. N. DODGE.
